(57) **CLAIM**

The ornamental design for a neck cooler, as shown and
described.

DESCRIPTION

FIG. 1 is a perspective view of a neck cooler showing my
new design;

FIG. 2 is a top view thereof;

FIG. 3 is a left view thereof;

FIG. 4 is a front side view thereof;

FIG. 5 is a right side view thereof;

FIG. 6 is a bottom view thereof; and,

FIG. 7 is a back view thereof.

The broken line shown in the drawings is included for the
purpose of illustrating portions of the neck cooler and forms
no part of the claimed design.
